UNITED STATES PATENT OFFICE.

LOUIS M. BROWN, OF BEVERLY, MASSACHUSETTS, ASSIGNOR TO UNITED SHOE MACHINERY COMPANY, OF PATERSON, NEW JERSEY, A CORPORATION OF NEW JERSEY.

HOLDDOWN DEVICE FOR LASTING-MACHINES.

1,095,266.

Specification of Letters Patent.

Patented May 5, 1914.

Application filed July 26, 1912. Serial No. 711,678.

To all whom it may concern:

Be it known that I, LOUIS M. BROWN, a citizen of the United States, residing at Beverly, in the county of Essex and State 5 of Massachusetts, have invented certain Improvements in Holddown Devices for Lasting-Machines, of which the following description, in connection with the accompanying drawings, is a specification, like referring 10 to characters on the drawings indicating like parts in the several figures.

This invention relates to hold-down devices for use in connection with lasting machines, such, for example as the well-known 15 commercial "No. 5 USMC lasting machine" which is shown in United States Letters Patent to Brock, No. 1,018,477, granted Feb. 27, 1912, to which reference may be had for a full description thereof.

20 The present invention is embodied in improved means for holding a hold-down foot to the hold-down arm.

It is desirable that different feet shall be used with different sizes and styles of shoes 25 and that convenient holding means may be provided which will provide adequate security and permit the foot to be conveniently removed and another foot substituted therefor and this invention comprises an advanced 30 tageous form of connection adapted for this purpose.

The several features of the invention will appear from the following description of the illustrated embodiment thereof and will 35 then be pointed out in the claims.

Figure 1 is a perspective view, partly in section, showing the manner of attaching the hold-down foot to the hold-down arm, the foot being shown in full lines detached and 40 in dotted lines in its operative position; Fig. 2 is a longitudinal section of the fore-part of a shoe showing in side elevation the hold-down foot applied thereto.

In Fig. 1 the character 2 indicates the arm 45 of a hold-down provided at its outer end with a stud 4 by which one end of the foot member 20 is secured thereto. The opposite end of the member 20 is provided with forwardly directed teeth to engage the insole behind the rib as shown in Fig. 2. The foot 50 20 is preferably resilient and the stud 4 by which it is attached to the arm 2 has a roughened head 6, which is adapted to en-

gage the innersole when the pressure of foot 20 against the shoe has caused the foot to yield. The stud 4 is flattened on its sides 55 at 8 and is maintained in fixed position in a hole in the arm 2 by a spring-held pin 10 having a reduced end which is forced outwardly into a hole 12 in the stud. Obviously 60 the stud may be released for removal by pushing back the pin 10 by means of a pointed instrument inserted through the hole 12. Upon the stem of the stud 4 is mounted to turn the resilient holding plate 65 14 which extends forwardly under and has supporting engagement at its front and rear ends with the lower face of the curved hold-down foot member 20. Near its front end the holding plate 14 has lips 16 bent up on 70 its opposite edges to form a seat in which member 20 is normally confined.

The foot 20 is provided at one end with an open slot 24 ending in an enlarged recess 22 and is assembled upon the end of the hold-down arm by pushing the slotted end upon the stud in the direction of the flattened sides of the stud until the stud rests in the recess 22 when the spring foot 20 may be rotated about the stud. The lips 16 of the 75 plate 14 are arranged to rest against opposite sides of the foot 20 and by reason of the tapered formation of the foot 20, Fig. 1, it cannot be pulled from the stud even when in line with the flattened sides thereof until the 80 lips 16 on the spring plate 14 are depressed below the plane of the foot 20. The spring plate 14, by crowding the foot 20 against the supporting arm 2, holds the foot frictionally 85 from rotation on the stud 4.

90 For different styles of shoes different hold-down feet may be provided, the construction shown providing means for readily detaching one foot and attaching another. To effect this the operator has only to insert a 95 pointed instrument between the spring plate 14 and the foot 20 and separate them sufficiently to disengage the lips 16 from the foot 20 so that the plate 14 and foot 20 may be swung relatively to each other about the 100 stud. The foot 20 may then be detached by rotating it into alignment with the hold-down arm and pulling it outwardly in the direction of said foot, the flattened sides of the stud then permitting it to pass through 105 the slot 24 of the foot 20. Other hold-down

feet may be attached to the hold-down arm by reversing the process described for removing the foot.

The use and operation of the described embodiment of the invention may be readily understood by those skilled in the art without further description, and it is also apparent that various modifications of the device as described may be made without departing 10 from the invention.

Having described my invention, what I claim as new and desire to secure by Letters Patent of the United States is:—

1. In a hold-down for lasting machines, a 15 hold-down foot, a support therefor, a headed stud having flattened sides, the said foot having a hole in one end with a relatively narrow open slot leading therefrom to admit the stud when moved thereover in the direction of the flattened sides, and means for holding the foot upon the stud.

2. A hold-down for lasting machines comprising a foot having a slotted end, a support therefor carrying a stud adapted to enter the slot, and a spring plate underlying the foot and secured to the stud in position to retain the foot in place upon the support.

3. A hold-down for lasting machines comprising a foot having a slot in its end which 30 terminates in an enlarged recess, a hold-down support, a flattened stud having a head secured to the support and adapted to enter the slot and to turn in the enlarged recess, and a spring plate underlying the 35 foot and securing it to the stud by means of upturned lips arranged to engage the sides of the foot.

4. In a machine of the class described, a 40 connection comprising an arm 2, a spring-pressed pin 10 mounted therein, a headed stud 4 having flattened faces and a hole 12 adapted to be engaged by said pin 10 to prevent rotation of the stud, and a member 20 having a slot 24 to admit the flattened portion of the stud 4, said slot having an enlargement to permit relative rotation of the stud and member.

5. In a machine of the class described, a 50 connection comprising a headed stud, a spring plate mounted thereon and having upturned lips, and a tapered member having a slot at its larger end adapted to engage the stud and to be held thereon by the engagement of the lips of the spring member upon its opposite tapered sides.

6. A hold-down for shoe lasting machines, comprising supporting and operating means movable over a shoe located in position to be lasted in the machine and having a 60 coupling formation, and a plate having a complementary coupling formation detachably engageable with the first mentioned coupling formation, one of said parts being provided

with a spring plate secured to it and engaging the other to resist a disengaging movement of the plate from its supporting and operating means. 65

7. A hold-down for shoe lasting machines comprising a supporting and operating means movable over a shoe located in position to be lasted in the machine and having a stud to engage the shoe bottom, a curved hold-down foot member adapted to engage the toe of the shoe innersole and having a detachable engagement with said means, a 70 resilient holding plate mounted to turn on the stud and extending forwardly under and having supporting engagement at its front and rear ends with the lower face of the curved foot member, and lips bent to restrain the front end of the holding plate and the foot member from relative turning movement. 75

8. In a hold-down for shoe lasting machines, an arm movable to extend transversely across the shoe, a hold-down member carried thereon to extend from said arm longitudinally of the shoe toward its toe, and a connection between said arm and member which is rigid against displacement by upward pressure thereon, comprising a member attaching stud snugly fitting the arm and depending therefrom, and a locking pin having a lower face perpendicular to the attaching stud, spring pressed from said arm 90 outwardly and having a reduced cylindrical portion seating in the attaching stud, the stud and the end portion of the arm having alined apertures through which access may be had to said reduced portion of the pin for 95 pressing it out of its seat in the stud. 100

9. In a hold-down for shoe lasting machines an arm movable to extend transversely across a shoe, a hold-down member carried thereon to extend from said arm 105 longitudinally of the shoe toward its toe, and a connection between said arm and member which is rigid against displacement by downward pressure applied to the shoe toe by said member, the connection comprising a member attaching stud having a stem extending upwardly into the arm, a seat in the arm snugly fitting the stem, and a locking pin extending from the arm transversely into the stem, said arm having an aperture 115 through which access may be gained to the pin to retract it for freeing the stem from the arm. 110

In testimony whereof I have signed my name to this specification in the presence of 120 two subscribing witnesses.
